Application June 14, 1950, Serial No. 168,073

14 Claims. (Cl. 206—80)

1

The present invention relates to a card particularly adapted for the display of bracelets, chains, and other flexible and sometimes resilient decorative articles.

Various articles of jewelry, such as bracelets, are often attached to supports for display purposes, to facilitate handling of the article, and when the bracelet is mounted in juxtaposition to appropriate decorative or trade-mark matter, for advertising purposes. More specifically, it is a relatively widespread practice to package bracelets such as wrist watch bracelets on individual cards so that the bracelets will be displayed to best advantage and will be properly identified as to type, make, composition and the like.

Display of a bracelet in such a manner is attractive and eye-catching, and often causes a prospective purchaser to prefer a bracelet thus packaged and displayed over one sold or displayed in bulk. However, a purchase is not usually consummated until the prospective purchaser has viewed the bracelet off the display card and preferably on his own wrist. This necessitates removal of the bracelet from the support and, if the customer is dissatisfied, or if the purchase is for gift purposes, the replacement of the bracelet on the support. This presents a serious problem to the jeweler as well as to the manufacturer.

Insofar as the jeweler is concerned, he is interested in a securing means which permits the bracelet to be readily removed from the support for exhibition and to be readily replaced on the support. The securing means must therefore be readily releasable without requiring any particular skill, special tools, or any appreciable time, since a jeweler, to make a single sale, may have to remove and replace a relatively large number of bracelets from their individual display supports. The jeweler also requires a securing means which permits the bracelet to be displayed in the most attractive manner possible, in order to facilitate the selling thereof.

Insofar as the manufacturer is concerned, he must not only satisfy the jeweler, thus insuring that his merchandise will be sold more readily than that of his competitors, but must also provide means for securing the bracelet to the display card which presents as little difficulty of assembly and manipulation as is possible, keeping uppermost in his mind the fact that the necessary labor involved in assembling the display card itself and hand-attaching the bracelets to the cards is an important factor in his overall costs. The securing means must be adequate to

retain the bracelet on the card through all the vicissitudes of packing, shipping, unpacking and handling, and the said securing means must be as inconspicuous as possible in order not to mar the attractive appearance of the bracelet.

Usually these two desiderata are contradictory, since the more positive the securing means, the more the appearance of the bracelet is marred.

A major problem involved in devising a proper type of securing means derives from the fact that bracelets are made in varying lengths, men's bracelets generally being longer than ladies' bracelets, and both men's and ladies' bracelets being available in different lengths so as to accommodate different size wrists. It is, of course, extremely desirable that any securing means be interchangeable for use with bracelets of different lengths and types, thus simplifying inventory, packaging and distribution.

Another problem involved arises from the fact that, particularly when watch bracelets are involved, the end portions of those bracelets differ according to whether the bracelets are to be used with men's watches or with ladies' watches. In men's watches the end portions of the bracelet are adapted to be secured between spaced lugs, and consequently take the form of tubes through which a retaining pin, preferably of the spring type, can be passed. In ladies' watches only a single apertured lug is employed on each side of the watch, and consequently the end portions of bracelets adapted to be used with ladies' watches are generally of ring-shape, the ring being openable so as to be engaged with the watch lug and then closable so as to be secured thereto. Two embodiments of display cards are therefore here disclosed, the first being particularly adapted for use with bracelets for ladies' watches and the second being particularly adapted for use with bracelets for men's watches. However, the second embodiment is usable with either type of bracelet and the first embodiment can, through suitable modification, be used with men's bracelets as well.

Bracelets and other flexible items of jewelry are best displayed when tensioned to their full length. Some bracelets are of the resiliently extensible type, and it may often be desired to display such bracelets in the slightly extended position which they will normally assume when in use, so that a realistic display appearance will be imparted to them. It therefore is most desirable that display structures be capable of retaining bracelets or the like in full length condition, and

sometimes, if desired, in slightly extended condition.

It is a prime object of the present invention to devise a display card structure which is capable of achieving the above desiderata and which is at the same time extremely inexpensive and capable of mass production and assembly at no appreciable increase in expense when compared to the less functionally satisfactory devices of the prior art. More specifically, the display cards of the present invention are capable of being adapted to bracelets of different lengths, of holding those bracelets in full length or partially extended condition, whichever may be desired, in permitting the bracelet to be readily removed from or replaced upon the display card and in so facilitating the initial assembly of the display card itself and of the bracelet on the display card as to give rise to a substantial saving in labor costs which will counterbalance any additional expense in materials involved.

To this end display cards are provided having a movable fastener secured to the card and frictionally held in adjusted position, the fastener being movable between one position, in which the bracelet is readily removed from or replaced onto the card, and another position, in which the bracelet is secured to the card in any condition desired. In order to display the bracelet to best effect, the structural portions of the fastener are positioned on the underside of the support, a finger or fingers extending upwardly therefrom to the top side of the support for engaging the bracelet end. The fastener proper is preferably constructed of one piece of material, and the same means which secures it to the support also provides for the frictional effect which permits it to stay in any position in which it may be placed.

With ladies' bracelets a single finger capable of being received within the ring-like end portions is sufficient. Such a fastener is disclosed in Figs. 1-5 of the specification. With men's bracelets a pair of fingers are employed, these fingers being adapted to be received within the tubular end portion of the bracelet at opposite sides thereof, the fingers being spring urged so as to grasp the tubular portion and hold it in position on the support. Such a fastener is disclosed in Figs. 6-14. This latter type of fastener could also easily be employed with the ring-type end portions of ladies' bracelets.

The term "display card" as used in this specification and in the claims has reference to an individual support upon which a single bracelet is mounted, and also comprehends within its scope other comparable structures such as a panel upon which a plurality of bracelets are mounted, each bracelet being individually removable and replaceable.

To the accomplishment of the foregoing objects and such other objects as may hereinafter appear the present invention relates to a display card and the like as defined in the appended claims and as described in the specification taken together with the accompanying drawings in which:

Fig. 1 is a top plan view of one embodiment of the present invention particularly adapted for use with ladies' bracelets or bracelets having ring-like end pieces;

Fig. 2 is a front elevational view of the display card of Fig. 1, a bracelet secured thereon being shown in broken lines;

Fig. 3 is a bottom plan view thereof;

Fig. 4 is a cross-sectional view thereof taken

along the line 4-4 of Fig. 1 on a slightly enlarged scale and showing a bracelet in position on the card, the fasteners on the card being in position for removal or replacement of the bracelet;

Fig. 5 is a view similar to Fig. 4 but showing the fasteners in position for securing the bracelet to the display card;

Figs. 5A and 5B are fragmentary three-quarter perspective bottom views of portions of the display card, showing alternative fastener embodiments;

Fig. 6 is a top plan view of another embodiment of the present invention particularly adapted for use with men's bracelets or bracelets having tubular end pieces;

Fig. 7 is a bottom plan view of the embodiment of Fig. 6;

Fig. 8 is an exploded perspective view of the fastener and clamp utilized therein;

Fig. 8A is a perspective view of an alternative embodiment of clamp;

Fig. 9 is a cross-sectional view of the embodiment of Fig. 6 taken along the line 9-9 thereof;

Fig. 10 is a cross-sectional view taken along the line 10-10 of Fig. 9;

Fig. 11 is a fragmentary top view, showing the fastener of Fig. 6 in conjunction with a men's watch bracelet, part of the top of the tubular end piece of that bracelet being broken away for purposes of clarity;

Fig. 12 is a cross-sectional view taken along the line 12-12 of Fig. 11;

Fig. 13 is a cross-sectional view taken along the line 13-13 of Fig. 11 and showing the fastener in a position in which the bracelet is slack on the support; and

Fig. 14 is a view similar to Fig. 13 but showing the fastener in a position such that the bracelet is stretched out to its full length.

The display card of the present invention, viewed generically, comprises the support generally designated A on the upper surface B of which a bracelet C or C' is adapted to be secured between the fasteners D and E. At least one of these fasteners, here shown as the fastener E, is movable toward and away from the other fastener D between one position in which the bracelet C is slack (see Figs. 4 and 13) and another position in which the bracelet C is grasped between the fasteners D and E and secured to the support A in stretched or taut condition (see Figs. 5 and 14). The movable fastener E is frictionally retained in whatever position it may be placed with respect to the support A so that the bracelet C will, when it is desired, remain tautly secured to the support A, or, once the fasteners D and E are positioned to slacken the bracelet C, they will remain in that position so as to facilitate replacement of the bracelet C.

The support A takes the form of an elongated member 2 of some suitable structural material such as cardboard which may have a layer of felt, plush or other fabric 4 secured to the upper surface B thereof in order to contrast with and enhance the appearance of the bracelet C adapted to be placed thereon. As specifically illustrated, the strip 4 of felt or the like does not extend all the way across the width of the member 2, in order to provide space for printing advertising and trade-mark matter, but this is not essential to the invention. The length of the member 2 is such that it can accommodate different standard lengths of bracelets.

Having specific reference first to the embodiment illustrated in Figs. 1-5; which embodiment

is particularly adapted for use with bracelets having ring-like end pieces such as are usually used to secure the bracelet to the lugs on ladies' watches, a slot 6 is provided in the support A and the strip 4 thereon near the end 17 thereof and the first fastener D is secured to the support A, a body portion 8 thereof being held on the underside 10 of the member 2 by means of rivet or eyelet 12, and a finger 14 being bent up therefrom so as to pass through the slot 6 and extend above the upper surface B of the support A, an extension 16 being bent at right angles thereto parallel to the top surface B of the support A and directed toward the adjacent end 17 of the support A. The finger 14 is adapted to be passed through an end ring 18 of the bracelet C when that bracelet is positioned on the support A.

A second and substantially elongated slot 20 is provided in the support A and the strip 4 adjacent the opposite end 22 thereof, the slot 20 being oriented so that it extends toward and away from the first fastener D and preferably longitudinally of the support A.

The second fastener E comprises a body 24 formed of some resilient material such as spring steel and provided with a slot 26 extending lengthwise thereof. At each end of the body 24 are upturned flanges 28, 28', the flange 28 being shown as extending across the entire width of the body 24 at one end thereof whereas each of the two flanges 28' extends only partially across the width of the body 24 at the other end thereof, an extension 30 of the body 24 projecting between the flanges 28' and being turned upwardly so as to define the finger 32 which extends through the slot 20 and above the support A. The finger 32, like the finger 14, is preferably provided with a portion 34 turned out at right angles thereto and parallel to the support A and directed toward the end 22 of the support A. The width of the slot 20 is only slightly greater than the width of the finger 32, the latter being slideable along the length of the slot 20 as the body 24 of the second fastener E moves relative to the support A.

The second fastener E is secured to the support A by means of an eyelet or rivet 36 passing through the support A and through the slot 26 in the body 24, a washer 38 being interposed between the rivet or eyelet 36 and the outer surface of the body 24.

The length of the eyelet or rivet 36 is such that the portion of the body 24 directly engaged thereby is held closer to the bottom surface 10 of the support A than the height of the flanges 28 and 28'. As a result the body 24 is bowed, as is clearly shown in Figs. 4 and 5, the ends of the flanges 28 and 28' being pressed against the lower surface 10 of the support A through the inherent resiliency of the body 24 and hence generating a frictional resistance to movement. The length of the slot 26 corresponds substantially to the length of the slot 20, the second fastener E thus being slideable in the direction of the slot 20 and hence toward and away from the first fastener D, the second fastener E being frictionally retained in whatever position it may be placed.

The display card of Figs. 1-5 can be assembled in an exceedingly simple manner. Supports A, with the felt or plush layer 4 secured thereto as desired, and with the slots 6 and 20 already formed therein, require merely two simple eyeletting operations for complete assembly of the structure. The first fastener D is placed in posi-

tion by threading the finger 14 through the slot 6 from the underside thereof until the body portion 8 lies snugly against the bottom surface 10 of the support A, the slot 6 being somewhat lengthened in order to permit that operation, and then the first fastener D is eyeleted into place. The second fastener E is then placed in position, its finger 32 passing freely through the slot 20, and an eyelet is then passed through the slot 26 in the body 24.

The manner of use of this embodiment of the present invention will in the main be apparent from the above discussion. When it is desired to place a bracelet upon the card, the second fastener E is moved toward the first fastener D, as shown in Fig. 4, until the fingers 14 and 32 are sufficiently close together so that the end links 18 and 18' of the bracelet C can be freely passed over the fingers 14 and 32 respectively and their respective outbent portions 16 and 34. Once the bracelet C has been placed in position it can be secured to the support A simply by moving the second fastener E away from the first fastener D until the fingers 14 and 32 engage the outer portions of the end links 18 and 18' of the bracelet C, thus holding the bracelet taut in full length condition, as shown in Figs. 2 and 5. In this position the bent portions 16 and 34 of the fingers 14 and 32 overlie the end links 18 and 18' and consequently prevent the bracelet from becoming detached from the support A. Since the second fastener E is frictionally retained in position, it will hold the bracelet C to the support A and even can maintain the bracelet in slightly resiliently extended condition, if the bracelet C is of that type, by further separating the two fasteners D and E. The length of the slots 20 and 26 is such that sufficient freedom of motion is given to the second fastener E so that it can accommodate itself to bracelets of varying lengths.

Of course, the first fastener D could itself be movable toward and away from the second fastener E, but for many applications only one movable fastener has been found necessary.

Alternative constructions of the fasteners E are disclosed in Figs. 5A and 5B. In Fig. 5A the flanges 28, 28' are dispensed with, dimples 29 being punched into the underside of the fastener body 24' so as to form upward projections which engage the underside 10 of the support member 2 and are pressed thereagainst by the eyelet 36, the fastener body 24' being preferably slightly bowed, as in Figs. 4 and 5, to insure good frictional engagement. Fig. 5B discloses a simplified embodiment in which no upward projections such as the flanges 28, 28' or the dimples 29 are provided the fastener body 24'' being flat and the eyelet 36 pressing against the underside 10 of the support member 2 so as to achieve good frictional engagement all along the length of the body 24'', but particularly at those portions of its length which may be adjacent the eyelet 36 at any given time.

Turning now to the embodiment of Figs. 6-14, which is particularly adapted for use with men's bracelets, the first fastener D and the second fastener E are both shown as movable toward and away from the other and are identical in construction. A description of one will therefore suffice for both.

The support member 2 and the fabric layer 4 are provided with two elongated slots 20, 20', one at each end thereof and each directed toward and away from the other, and it is through these slots that the fingers of the fasteners D and E are passable. Each fastener comprises a U-shaped body

defined by a base 40 and two substantially parallel arms 42, the arms terminating in fingers 44 extending upwardly therefrom and preferably terminating in end portions 46 substantially perpendicular to the fingers 44 and to the arms 42 and parallel to the top support surface B. The end portions 46 are, as here illustrated, directed away from one another, and the arms 42 are resiliently urged apart by means of the inherent resilience of the fastener itself, said fastener preferably being formed of some inherently resilient material such as spring steel or the like, and most conveniently being formed from steel strip or wire stock appropriately bent to shape.

The base 40 and arms 42 of the fastener are positioned on the underside of the support member 2 and are urged into frictional engagement with the bottom surface 10 of the support A by means of a clamp generally designated 48. This clamp comprises a central portion 50 having prongs 52 extending upwardly therefrom, the prongs being adapted to pass through the member 2 and the fabric layer 4 and, by being bent over, to secure the clamp 48 to the support A. On either side of the central portion 50 of the clamp 48 are two wing portions 54, each of these portions being dished or concaved along their length, so that when the clamp 48 is secured in position on the underside of the support A, passages are defined between the wing portions 54 and the bottom surface 10 of the support A. The arms 42 of the fastener extend through these passages, and the passages are preferably somewhat wider than the arms 42 in order that the arms 42 may have limited degree of freedom of motion toward and away from one another. The cross-sectional depth of these passages at their deepest point is slightly less than the thickness of the arms 42, so that the said arms and the base 40 of the fastener are pressed tightly against the bottom surface 10 of the support A, thus giving rise to a frictional engagement between the fastener, the support A, and the clamp 48. As may be seen particularly from an examination of Figs. 10 and 12, the concavity of the two portions 54 is such in conjunction with the thickness of the arms 42 of the fastener that the said arms 42 are slightly pressed into the lower surface 10 of the support A, causing a slight deformation of said lower surface 10.

The tendency of the arms 42 in the form here specifically disclosed is to spread apart, the degree of such spreading being limited either by engagement of the fingers 44 with the sides of the slot 20 through which they pass, by the engagement of the arms 42 with sides of the passages defined by the clamp wing portions 54, or by both. Because of the width of these passages the arms 42, and consequently the fingers 44, can be moved toward one another, thus permitting the oppositely directed end portions 46 to be received inside the tubular end piece 56 of the bracelet C', entering therein through the slot 58 formed in the underside thereof (see Figs. 11 and 12). So long as the outwardly extending finger end portions 46 engage inside the tubular bracelet end piece 56, that end piece will be positively secured on the support A. This engagement may be accomplished while the bracelet C' is in slack position, as shown in Figs. 11 and 13, and thereafter the fastener E may be slid with respect to the support A until the bracelet is tautly stretched out full length or even slightly expanded if that is desired, as illustrated in Fig. 14. It will also be apparent that this same two-finger

structure can be used with the ring-like bracelet end portions 18 on ladies' bracelets such as those disclosed in Figs. 4 and 5.

When, as here specifically disclosed in Figs. 11 and 12, the sides of the slot 58 formed in the tubular end piece 56 of the bracelet C' are more closely spaced than the sides of the slot 20, the fingers 44 of the fastener E, and consequently the arms 42 thereof, will, when the bracelet C' is secured on the support A, be maintained in a position closer to one another than would normally be the case. It will be noted that this positioning of the arms 42 will, by reason of the tapered cross sectional shape of the passages through which the arms 42 are moved, be pressed more firmly into frictional engagement with the bottom surface 10 of the support A and with the wing portions 54 of the clamp 48, being wedged between them. Hence, once the fastener E has been engaged with a bracelet C' of the type here specifically illustrated, it will be more firmly frictionally positioned on the support A than when it is not so engaged.

Because of the resilience of the arms 42 and their ability to move toward and away from one another, the tubular bracelet end piece 56 may be secured to the fastener in an expeditious and simple manner. One of the outwardly directed finger end portions 46 may be caused to enter the tubular end piece 56 through the slot 58. The bracelet may then be moved laterally with respect to the support A, bending the fastener arm 42 already secured to the bracelet, until the other outwardly directed finger end portion 46 is received within the tubular end piece 56. Thereafter the bracelet is released and the resilience of the first-engaged arm 42 will cause the bracelet to move back laterally with respect to the support A until both outwardly extending finger end portions 46 are secured within tubular end piece 56, that end piece being thus automatically centered on the support A. To disengage the bracelet from the display card the reverse operations are employed.

It will be apparent that the above construction can be modified to permit the fastener to engage in tubular bracelet end pieces 56 not provided with the slot 58 by utilizing a fastener whose arms 42 will resiliently tend to move together, and by so shaping the fingers 44 and end portions 46 that those end portions will be directed toward one another and separated sufficiently so as to be movable into the tubular end piece 56 from the sides thereof. This construction has the disadvantage that the fastener will be partially visible, whereas the construction here specifically disclosed is completely invisible when the bracelet is secured thereto, the bracelet C' being maintained on the support A in optimum condition without any visible distracting disfigurement.

Fig. 8A discloses an alternative clamp construction in which prongs 52' are punched from the middle of the central portion 50' of the body of the clamp 48'. It will be noted that the prongs 52' are pointed, thus facilitating their penetration of the support member 2, and that said pointed construction is achieved without waste of material and in a manner convenient for mass production by punching each prong 52' from adjacent areas of the central portion 50' of the fastener 48'.

Assembly of the display card of Figs. 6-14 will be apparent from its construction. The fasteners D and E are first placed in position, after which

the clamps 48, so placed that the arms 42 of the fasteners are pressed between the surface 10 of the support A and the concave wing portions 54, are secured to the support A.

In both embodiments each of the fasteners D and E can be integrally formed in a cutting, stamping or bending operation well adapted for mass production and consequently may be produced very inexpensively. The clamp 48 of the embodiment of Figs. 6-14 can be similarly produced. Assembly of the display card can be carried out by semi-skilled personnel in a semi-automatic and expeditious manner. Thus the cost of the display card is not appreciable.

The facility of use of the present invention is, however, extremely marked when compared with the prior art structures. Not only may bracelets of varying lengths be accommodated on the same display card and by the same structure, but each bracelet may be displayed in a manner best adapted to show off its most attractive attributes and each bracelet may be removed from or replaced on the support in no time at all by unskilled personnel and without in any way destroying or distorting the display card structure itself.

Only two specific embodiments of the present invention are here disclosed but it will be apparent that many variations may be made in the design thereof all within the spirit of the invention as defined in the following claims.

I claim:

1. A display card for bracelets and the like comprising a support on the top surface of which the bracelet or the like is adapted to be placed, a first fastener projecting above said top surface for engaging one end of said bracelet, said support having a slot spaced from said first fastener and extending toward and away therefrom, and a second fastener comprising a U-shaped resilient body having a base and arms mounted below said support, the ends of said arms having fingers passing through the slot in said support and projecting above the top surface of said support for engaging the other end of said bracelet, said fingers being urged apart by the resilience of said U-shaped body, and a clamp secured to said support and having passages through which the arms of said U-shaped body are movable, said clamp pressing said body against and into frictional engagement with the bottom surface of said support, said second fastener thus being manually movable toward and away from said first fastener and frictionally retained in the position to which it is moved.

2. The display card of claim 1, in which said passages are tapered in cross-section, so that when said arms are moved toward or away from one another they are wedged therein, thus increasing the frictional force tending to retain said second fastener in its position along said support.

3. The display card of claim 1 in which said clamp comprises a central portion, prongs extending upwardly therefrom and passing through said support for securing said clamp thereto, and concave wing portions on either side of said central portion, said wing portions defining, in conjunction with the bottom surface of said support, the passages through which the arms of said U-shaped body are movable.

4. A display card for bracelets and the like comprising a support on the top surface of which the bracelet or the like is adapted to be placed, a first fastener projecting above said top surface for engaging one end of said bracelet, said sup-

port having a slot spaced from said first fastener and extending toward and away therefrom, and a second fastener comprising a U-shaped resilient body having a base and arms mounted below said support, the ends of said arms having fingers passing through the slot in said support and projecting above the top surface of said support for engaging the other end of said bracelet, said fingers being urged apart by the resilience of said U-shaped body, and a clamp secured to said support and having passages through which the arms of said U-shaped body are movable, said passages being wider than said arms so as to permit a degree of relative motion of said arms toward and away from one another, said clamp pressing said body against and into frictional engagement with the bottom surface of said support, said second fastener thus being manually movable toward and away from said first fastener and frictionally retained in the position to which it is moved.

5. The display card of claim 4, in which said passages are tapered in cross-section, so that when said arms are moved toward or away from one another they are wedged therein, thus increasing the frictional force tending to retain said second fastener in its position along said support.

6. A display card for bracelets and the like comprising a support on the top surface of which the bracelet or the like is adapted to be placed, a first fastener projecting above said top surface for engaging one end of said bracelet, said support having a slot spaced from said first fastener and extending toward and away therefrom, and a second fastener comprising a U-shaped resilient body having a base and arms mounted below said support, the ends of said arms having fingers passing through the slot in said support and projecting above the top surface of said support for engaging the other end of said bracelet, said fingers being urged apart by the resilience of said U-shaped body and having oppositely directed end portions substantially parallel to said top surface and extending substantially perpendicular to the length of said slot, and a clamp secured to said support and having passages through which the arms of said U-shaped body are movable, said clamp pressing said body against and into frictional engagement with the bottom surface of said support, said second fastener thus being manually movable toward and away from said first fastener and frictionally retained in the position to which it is moved.

7. The display card of claim 6, in which said passages are tapered in cross-section, so that when said arms are moved toward or away from one another they are wedged therein, thus increasing the frictional force tending to retain said second fastener in its position along said support.

8. The display card of claim 1 in which said clamp comprises a central portion, prongs extending upwardly therefrom and passing through said support for securing said clamp thereto, and concave wing portions on either side of said central portion, said wing portions defining, in conjunction with the bottom surface of said support, the passages through which the arms of said U-shaped body are movable.

9. A display card for bracelets or the like comprising a support on the top surface of which a bracelet or the like is adapted to be placed, a first fastener projecting above said top surface for engaging one end of said bracelet, and a sec-

11

ond fastener adjustably mounted on said support projecting above said top surface, spaced from said fastener and movable toward and away from said first fastener for engaging the other end of said bracelet, said second fastener comprising a pair of fingers resiliently urged apart, means for frictionally holding said second fastener in adjusted position on said support.

10. The display card of claim 9, in which said fingers have oppositely directed end portions substantially parallel to said top surface.

11. A display card for bracelets or the like comprising a support on the top surface of which a bracelet or the like is adapted to be placed, a first fastener projecting above said top surface for engaging one end of said bracelet, said support having a slot spaced from said first fastener and extending toward and away therefrom, and a second fastener adjustably mounted on and below said support for motion in the direction of said slot and having a pair of fingers passing through said slot and projecting above said top surface for engaging the other end of said bracelet, said fingers being resiliently urged apart, and means for frictionally holding said second fastener in adjusted position on said support.

12. This display card of claim 11, in which said fingers have oppositely directed end portions substantially parallel to said top surface and extending substantially perpendicular to the length of said slot.

13. A display card for bracelets and the like comprising a support on the top surface of which a bracelet or the like is adapted to be placed, a first fastener projecting above said top surface for engaging one end of said bracelet, said sup-

port having a slot spaced from said first fastener and extending toward and away therefrom, a second fastener comprising a body mounted on the undersurface of said support and having a pair of fingers passing through said slot and projecting above said top surface for engaging the other end of said bracelet, said fingers being resiliently urged apart, and a unitary fastening means of fixed effective length simultaneously engaging said support and said second fastener and pressing said second fastener against the undersurface of said support, said second fastener being manually movable in the direction of said slot to adjusted position and retained in said adjusted position by friction.

14. The display card of claim 13, in which said fingers have oppositely directed end portions substantially parallel to said top surface and extending substantially perpendicular to the length of said slot.
